Inventor:

Joseph Lauferty
by Phillips Abbott
his Attorney,

UNITED STATES PATENT OFFICE.

JOSEPH LAUFERTY, OF NEW YORK, N. Y.

SUSPENDER-END.

SPECIFICATION forming part of Letters Patent No. 390,303, dated October 2, 1888.

Application filed May 21, 1888. Serial No. 274,601. (No model.)

To all whom it may concern:

Be it known that I, JOSEPH LAUFERTY, a citizen of the United States, residing in New York, in the county and State of New York, 5 have invented a new and useful Improvement in Suspender-Ends, of which the following is a full, complete, and exact specification, reference being had to the annexed drawings.

My invention, as stated, relates to an improvement in suspender-ends; and it consists in constructing each of the suspender-ends of leather—preferably chamois skin or kid—made into tubular form, filled with a strengthening-filler of cord, then flexed upon itself at about 15 its central portion, and the meeting edges sewed together above the loop which forms the button-hole.

Suspender-ends have heretofore been made of strips of leather sewed to strips of cloth, 20 also as shown in the United States Letters Patent granted to me dated March 21, 1882, No. 255,175.

The suspender-ends made by me were found objectionable because of their clumsy appearance, especially at the button hole or loop; and also, because of the thickness of the material at the button-hole, it was inconvenient to pass the loop under the button, especially 25 when it was tightly sewed to the pantaloons. Moreover, by my said former invention, the overlapping pieces had to be stitched down both edges. This added considerably to the expense of the ends; and also they were thick 30 and clumsy at the edges, owing to the four thicknesses of material there present.

I am also aware that suspender-ends have been made by folding a piece of braid upon itself and uniting the meeting edges, as shown in the Shenfield patent of November 9, 1875, 40 No. 169,855.

In the drawings, the same reference-letters indicate the same parts in all the figures.

Figures 1, 2, 3, and 4 illustrate various stages in the manufacture of the suspender-45 ends, as will be hereinafter explained; and Fig. 5 illustrates a completed suspender-end.

I make my improved ends as follows: The leather is first cut into strips of the proper length and width to form a suspender-end 50 from a single piece, as seen in Fig. 1, at A. It is then folded lengthwise, the wrong side

being out, and is stuck or stitched together on the edges, as shown at B, Fig. 2. It is then turned inside out, as seen in Fig. 3. The cord or strengthening filler C is then 55 drawn through it, as seen in Fig. 4. It is then preferably flattened with an iron, or by any suitable pressure, and is then bent flat-wise at about its median part, and preferably in such manner that the seams shall meet 60 to each other. The two parts thus lying side by side are then firmly stitched to each other, preferably, but not necessarily, by a zigzag stitch, which spans the seam between the side-by-side parts, as seen at D in Fig. 5. The 65 stitches commence somewhat above the looped part, as at E, thus forming a button-hole at the lower looped part. The upper unfinished extremities are then placed between the folded sides of the ordinary clip or attaching piece 70 seen at F, and stitched thereto as usual in the construction of suspender-ends. It is obvious that the leather may be made in tubular form, rightside out, which will obviate the subsequent turning, and then stitched as before. 75

By my invention it will be seen that I obtain a handsome, durable, economical, and very desirable suspender-end, which is made from leather, thus having a surface and appearance specially desired in suspender-ends, and that I can 80 use a soft, pliable, or, in other words, fine quality of leather—such as chamois skin or kid—which, being re-enforced by the filler of cord, will serve the purposes of a suspender-end admirably, and will retain its shape perfectly until worn out; also, that the edges of the end are rounded, thus presenting a fine finished appearance, and that the folded ends are united to each other by a single row of stitches. 85

I claim—

As an improved manufacture, a suspender-end comprising a leather tube filled with a reinforcing cord and bent upon itself to form a button-loop, the meeting parts of the bent tube being sewed to each other by a zigzag line of 95 stitches which enter each folded part and span the seam between them, substantially as set forth.

JOSEPH LAUFERTY.
